(57) **CLAIM**

The ornamental design for a rotating broiling rack, as shown and described.

DESCRIPTION

1. Rotating broiler rack

1.1 is a front perspective view of a rotating broiler rack and its components showing my new design;

1.2 is a back perspective view thereof;

1.3 is a side perspective view thereof;

1.4 is a view of a first component of the rotating broiler rack as shown in 1.1-1.3;

1.5 is a view of a second component of the rotating broiler rack as shown in 1.1-1.3;

1.6 is a view of a third component of the rotating broiler rack as shown in 1.1-1.3; and

1.7 is a view of a fourth component of the rotating broiler rack as shown in 1.1-1.3.
